Primary Examiner — Mary Ann Calabrese

(74) Attorney, Agent, or Firm — Crestron Electronics, Inc.

(57) **CLAIM**

The ornamental design for a wall mounted sign, as shown and described.

DESCRIPTION

FIG. 1 shows a front perspective view of a wall mounted sign illustrating the new design.

FIG. 2 shows a right view of the wall mounted sign illustrated in FIG. 1.

FIG. 3 shows a front side view of the wall mounted sign illustrated in FIG. 1.

FIG. 4 shows a left side view of the wall mounted sign illustrated in FIG. 1; and,

FIG. 5 shows a back view of the wall mounted sign illustrated in FIG. 1.

The broken line showing of elements on the wall mounted sign illustrate portions of the article and form no part of the claimed design.

1 Claim, 5 Drawing Sheets
